C. C. STIRLING.
ELECTRIC SNAP SWITCH.
APPLICATION FILED OCT. 19, 1917.

Patented May 28, 1918.

UNITED STATES PATENT OFFICE.

CLARENCE C. STIRLING, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SNAP-SWITCH.

1,267,603.

Specification of Letters Patent. Patented May 28, 1918.

Application filed October 19, 1917. Serial No. 197,421.

To all whom it may concern:

Be it known that I, CLARENCE C. STIRLING, a citizen of the United States, residing at Hartford, in the county of Hartford 5 and State of Connecticut, have invented certain new and useful Improvements in Electric Snap-Switches, of which the following is a specification.

This invention relates to electric snap switches. The primary purpose I have in view is the provision in an article of the character set forth, of means by which a switching member can be easily and readily snapped between on and off positions 15 through the agency of a single element, which is generally but not essentially, operated by hand.

In the drawings accompanying and forming part of the present specification I have 20 shown in detail one convenient form of embodiment of the invention which to enable those skilled in the art to practise the same will be set forth fully in the following description. The novelty of the invention 25 will be included in the claims following said description.

Referring to said drawings:

Figure 1 is a front elevation of a switch 30 involving the invention. Fig. 2 is a longitudinal vertical section on the line 2—2 of Fig. 3, looking in the direction of the arrows.

Fig. 3 is a longitudinal central section on the line 3—3 of Fig. 2, looking in the direction of the arrows and with part of the actuator broken away.

Fig. 4 is a detail sectional view, the section being on the line 4—4 of Fig. 3, looking in the direction of the arrow and showing the switching member and certain other parts in different positions by full and dotted lines.

Figs. 5 and 6 are diagrams showing different ways of wiring up.

Like characters refer to like parts throughout the several views which are on different scales.

The device as shown comprises a support such as the back 2 usually of some insulating material. In addition to the back 2, is a casing 3 customarily formed from sheet metal and receiving within it the base 2, the parts in question jointly supporting and receiving the switching mechanism and

certain associated parts as will hereinafter 55 more particularly appear. The metal casing or cap 3 preferably incloses a lining as 4 of some suitable insulating material. There may be and preferably are extending through the body 2 the three screws 5, 6 and 7, the screws being generally triangularly arranged or touching the points of a triangle. To one of the screws 5 and 6 a wire as 8 may be connected, while to the third screw 7 a wire as 9 may be connected. 60

I have shown in Fig. 5 how the wire 8 is connected to the screw 6 and in Fig. 6 I have illustrated how said wire may be connected with the screw 5 and a wire 8' connected with the screw 6. It will be clear, therefore, 70 that if the screws 6 and 7 in the arrangements shown by Fig. 5 are bridged electrically, the switch will be on or the circuit closed. In Fig. 6 it is clear that if the screws 5 and 7 and 6 and 7 be electrically bridged, 75 the circuits will be closed in alternation. In Fig. 5 I have shown by full and dotted lines the circuit as respectively open and closed, while in Fig. 6 I have illustrated by full and dotted lines the two circuits re- 80 spectively closed. I will hereinafter set forth how these particular results can be achieved.

Between the heads of the screws 5 and 6 and the insulating support 2 as best shown 85 by Fig. 3, I may dispose washers 10, and between the inner ends of the washers and the heads of the screws are carried contacts 11 which alternately receive the free end of a switching member as will hereinafter more 90 particularly appear. The incoming and outgoing wires may be held to the screws 5, 6 and 7 in any desirable manner as by nuts 12 on the rear or outer ends of the screws as best shown by Fig. 3. 95

In the housing presented jointly by the back 2 and casing or shell 3 is the body 13 of an actuator such as that denoted in a general way by 14. This body, which generally consists of an elongated flat strip fits flatwise and travels longitudinally on the support 2. As shown it has near one end the longitudinal slot 15 through which the screw 7 extends, the other end being furnished with a projection 16 to travel in the longitudinal slot 17 of the support 2. In this way I provide for the proper guiding in a straight path of the body 13 which as I

have already indicated is a part of the actuator. This body terminates in the projection 18 which is provided with an outwardly extending stud 19 projecting through registering perforations 20 in the casing or shell 3 and lining 4, so as to be within easy reach of the user of the switch. The actuator 14 is provided at its rear end with a projection 21 constituting a suitable shiftable stop as 10 will hereinafter appear.

The screw 7 serves as a suitable pivot for a switching member as 22, said switching member being in the form of an elongated strip having a wedge or arrow-like head 23 15 which is perforated to receive the inner end and plain portion of the screw 7, the switching member 22 as will be inferred, turning on the screw as a pivot. The tail portion of the switching member 22 has notches 24 20 formed in its sides, and these are adapted alternately to receive the stop 21 as shown best by full and dotted lines in Fig. 4. The actuator 14 is furnished with a suitable operating portion such as the spring 25, the 25 butt of which is secured in a notch 26 in the stop 21 as shown best by Fig. 2. This operating portion 25 is resilient and is somewhat elongated, its free end being furnished with a finger 26 adapted alternately to 30 operate with the lateral faces of the wedge head 23.

When the switching member 22 is at rest as shown best by full and dotted lines in Fig. 4, the finger 26 will be forward of 35 and slightly at one side of the point of the wedge head 23. It will be assumed that the tail or free portion of the switching member 22 is against the contact 5 and that the circuit is thus open as shown for illustration by full lines in Fig. 5. To close the 40 circuit the switching member 22 will be moved to the dotted line position in Fig. 5 which would be from the full line to the dotted line position of Fig. 4. It will be assumed that this is desired. In such event, 45 therefore, the projection 19 is moved rearwardly or upwardly in Figs. 2, 3 and 4, as shown for instance by the dotted lines of Fig. 2 which indicates the extreme position. 50 As the actuator 14 is thus moved, it follows that the spring arm or operating portion 15 is carried therewith and after the parts have moved a comparatively short distance, the finger 26 will engage the face 27 of the 55 wedge head 23 and will ride along said face as shown by the series of dotted circles in Fig. 4. This results naturally in moving the spring arm 23 laterally or bending it as shown by dotted lines in Fig. 2. The spring 60 arm is as a result tensioned, so that when the projection 21 passes entirely free of the tail portion of the switching member 22, the switching member will be instantly snapped from the full line to the dotted line 65 position in said view by the force of the

spring 25. When the finger of the operator is removed from the projection 19, the spring 20 which is stretched and which is connected respectively with the screw 7 and the screw 81 on the strip 18 will return said strip 18, and as a consequence the projection 19 to the initial position thereof which it is shown as occupying in Fig. 2 and also in Fig. 3. During this forward movement the finger 26 traverses the face 27, passes out of 75 contact therewith and resumes its initial position as shown by the full lines in said Fig. 4. To move the switching member 22 from the dotted line position to the full line position in said Fig. 4, the same action 80 is followed, except that the finger 26 will ride along the face 28.

What I claim is:

1. The combination of a switching member having a wedge-like head, an actuator, 85 a yieldable finger on the actuator adapted to traverse the wedge head and thus shift the switching member when the latter is released, and a detent to prevent movement of the switching member until the actuator 90 has traveled a certain distance.

2. The combination of an oscillatory switching member having a wedge-like head, a slidable actuator, a yieldable finger on the actuator adapted to traverse the 95 wedge head to thus shift the switching member, and a detent rigid with the actuator, to prevent movement of the switching member until the actuator has traveled a certain distance.

3. The combination of an oscillatory switching member having a wedge-like head, an actuator to travel in a straight path, the pivot of the switching member guiding the actuator, a yieldable finger on 105 the actuator adapted to traverse the wedge head to thus shift the switching member, and a detent rigid with the actuator to prevent movement of the switching member until the actuator has traveled a certain 110 distance.

4. The combination of an oscillatory switching member having a wedge-like head, an actuator, to travel in a straight path, a yieldable finger to traverse the 115 wedge head to thus oscillate the switching member, and a detent to prevent movement of the switching member until the actuator has traveled a certain distance, the detent being carried by the actuator and the yieldable 120 finger in turn being connected therewith.

5. The combination of an actuator movable in a straight line, a guiding element for the actuator, an oscillatory switching member having a wedge-like head, supported by 125 said guiding member, a yieldable finger to traverse the wedge head to thus shift the switching member, and a detent on the actuator to prevent movement of the switching member until the actuator has traveled 130

a certain distance, the yieldable finger being connected with the actuator.

6. The combination of an actuator, means for causing the movement of the actuator 5 in a straight path, an oscillatory switching member having a wedge-like head, a detent connected with the actuator, the switching member having notches to be entered by the 10 detent in alternation, and a yieldable finger connected with the detent, the finger being adapted to traverse the wedge head to thus shift the switching member, and the detent serving to prevent movement of the switching member until the actuator has traveled 15 a certain distance.

7. The combination of a switching member having a wedge-like head, an actuator, a spring finger on the actuator adapted to traverse the wedge-head and thus shift the switching member when the latter is released, and a detent to prevent movement of the switching member until the actuator has traveled a certain distance. 20

In testimony whereof I affix my signature in the presence of two witnesses.

CLARENCE C. STIRLING.
